TURRET HEAD FOR DRILL PRESSES

Graham C. Scates, Altadena, Calif.

Application April 1, 1943, Serial No. 481,435

3 Claims. (Cl. 77—25)

This invention relates to a turret head and more particularly to a turret head that is adapted to be used in connection with a drill press and has for its main object a novel means by which to drive individual drill chucks of the turret head.

Another object of this invention is to provide a turret head including a novel means to disengage a driving clutch means from individual chucks.

Another object of this invention is to provide a novel means to change from one drill size to another in a drill press turret.

Another object of this invention is to provide a novel stop member to prevent rotating of the entire turret drill unit.

Other and further important objects of this invention will be apparent from the disclosures in the specification and the accompanying drawings.

This invention in its preferred form is illustrated in the drawings and hereinafter more fully described.

Fig. 1 is a sectional front view of a drill press turret embodying the features of my invention;

Fig. 2 is a side view showing a drill chuck aligned in its proper position, and

Fig. 3 is a bottom plan view showing a preferred arrangement of the chuck spindles.

Referring to the drawings by reference characters I have shown my invention as embodied in a turret head which is indicated generally at 10. As shown the head includes an upper housing 11 having a lower circular base member 12 set at an angle thereto. The housing also includes a trigger supporting portion 13 shown as extending perpendicular to the casing member 12. Enclosed in the upper portion of housing 11, and supported by a bearing member 14, I provide a drive shaft 15 being held in position by a collar 16 which threadedly engages the upper portion of bearing member 14 as at 17. The inner end of the bearing member 14 engages a shoulder 17a in the housing 11 and has an internal flange 18 which engages the lower end 19 of an annular member 20 integral with, and spaced from, the drive shaft 15 to limit its downward movement.

The space 20' between the member 20 and the drive shaft receives the upper end of a compression spring 21 which encircles a reduced lower portion 22 of the drive shaft 15. The lower end of the spring seats upon the upper surface of an upper clutch member 23. The lower portion 22 of the drive shaft is keyed to

the clutch member 23 by a pin 24 arranged in the portion 23 and sliding in a slot 25 in the portion 22.

The upper clutch member 23 has an annular slot 26 which is adapted to be engaged by the tip 27 of a shift lever 28 shown as pivotally mounted at 29. The lower end of the clutch member 23 is movably mounted in a bearing member 31 in a bore 32 and has clutch teeth 33 on the lower end thereof which are adapted to engage clutch teeth 34 on a lower clutch member 35 in any one of a plurality of spindles 36, 36a, 36b, 36c or 36d (see Fig. 3) located in a lower housing member 37.

Each spindle 36 consists of a bearing member 38 which has end bores 38' connected by a reduced bore 38'' thus forming shoulders 39 the upper of which supports a washer 40 which in turn supports the lower clutch member 35. Threadedly engaging clutch member 35 and enclosed in bearing 36 I arrange a chuck spindle 41 which has a shoulder 42 engaging the lower shoulder 39 and thus limiting its upward movement. The upper end of the chuck spindle is reduced in diameter and threaded as at 41a to engage similar threads in the lower chuck member 35. The spindle 41 has a tapered portion 43 adapted to engage a drill chuck 44 (see Fig. 2).

The lower housing member 37 is arranged against the flat side 45 of portion 12 of upper casing 11 so that it may be rotated against the aforesaid upper casing and is held in place by a nut 46, which threadedly engages a post 47 on the base member 12 at 48, the post extending through a hole 49 in lower housing 37.

The nut 46 is tightened against a shoulder 50 in the lower housing 37 adjoining hole 49. The lower portion 12 of upper casing 11 and the lower casing 37 have recesses 51 and 52 to allow clearance for the correct alignment of upper and lower clutch members 23 and 35.

Extending from and threaded engaging portion 12 (see Fig. 2) I provide a stop rod 53 which is adapted to rest against a drill press column to prevent rotation of the turret unit when in operation.

It will be seen that rotation of the drive shaft 15 will, through pin 24, drive clutch member 23 and through teeth 33 and 34 drive clutch member 35 to thus turn spindle 43 which in turn rotates a drill chuck or other device as indicated at 44. When changing from one drill chuck to another the shift lever 28 is depressed thus raising clutch member 23 and compressing spring 21 and separating the teeth 33 and 34 so that the lower

casing member 37 may be rotated to the correct position for the desired drill chuck. The lever 28 is then released thus allowing spring 21 to depress clutch 23 and allow teeth 33 to engage the teeth of the lower clutch member of the newly selected drill chuck.

The bearing member 14 has a shrink fit in the housing and the bearing member 38 has a shrink fit in the lower housing 37.

The clutch members provide means for driving the spindles 41 and also provide means for holding the housing 37 in the correct position wherein the working chuck is aligned with the drive shaft.

Having thus described my invention and the present preferred embodiments thereof, I desire to emphasize the fact that many modifications may be resorted to in a manner limited only by a just interpretation of the following claims.

Having thus described my invention, I claim:

1. A turret head for a drill press comprising a housing having a base member thereon, said housing having an axial bore and having a shoulder intermediate the length of the axial bore, the base member having a planar face the axis of which is inclined to the axis of the bore, a bearing in the upper portion of said housing bore and engaging said shoulder, said bearing having an internal flange, a drive shaft in said bearing, means to hold the drive shaft against axial movement, said drive shaft having an intermediate shoulder and having a reduced lower portion, said drive shaft shoulder engaging said internal flange, said drive shaft having an annular recess adjacent to the reduced portion, a second bearing member in the lower portion of said bore, a clutch member within the bore and slidably in the second bearing member, means for shifting said clutch member, said drive shaft having means to prevent relative rotation between said drive shaft and said clutch member, a spring in said annular recess and engaging the upper end of said clutch member, said clutch member having teeth in the lower face thereof, a rotary head on said base member, said head having an aperture therein, a bearing member mounted in said head aperture, said bearing member having large upper and lower bores and an intermediate reduced bore, said reduced bore providing shoulders at each end thereof, a chuck spindle having a shank arranged in said large lower bore and having a shoulder engaging the lower of said shoulders, said spindle having an intermediate cylindrical portion in said intermediate bore and above the shoulder and having an upper end in said large upper bore, and a second clutch member secured to said spindle and having teeth in the upper face thereof.

2. A turret head for a drill press comprising a housing having a base member thereon, said housing having an axial bore and having a shoulder intermediate the length of the axial bore, the base member having a planar face the axis of which is inclined to the axis of the bore, a bearing in the upper portion of said housing bore and engaging said shoulder, said bearing having an internal flange, a drive shaft in said bearing, means to hold the drive shaft against axial movement, said drive shaft having an intermediate shoulder and having a reduced lower portion, said drive shaft shoulder engaging said internal

flange, said drive shaft having an annular recess adjacent to the reduced portion, a second bearing member in the lower portion of said bore, a clutch member within the bore and slidably in the second bearing member, means for shifting said clutch member, said clutch member having a pin therein, said drive shaft having a longitudinal slot receiving said pin, a spring in said annular recess and engaging the upper end of said clutch member, said clutch member having teeth in the lower face thereof, a rotary head on said base member, said head having an aperture therein, a bearing member mounted in said aperture, said bearing member having large upper and lower bores and an intermediate reduced bore, said reduced bore providing shoulders at each end thereof, a chuck spindle having a shank arranged in said large lower bore and having a shoulder engaging the lower of said shoulders, said spindle having an intermediate cylindrical portion in said intermediate bore and above the shoulder and having a threaded upper end in said large upper bore, and a second clutch member threadedly engaging said spindle threaded portion, said clutch member having teeth in the upper face thereof.

3. A turret head for a drill press comprising a housing having a base member thereon, said housing having an axial bore and having a shoulder intermediate the length of the axial bore, the base member having a planar face the axis of which is inclined to the axis of the bore, a bearing in the upper portion of said housing bore and engaging said shoulder, said bearing having an internal flange, a drive shaft in said bearing, means to hold the drive shaft against axial movement, said drive shaft having an intermediate shoulder and having a reduced lower portion, said drive shaft shoulder engaging said internal flange, said drive shaft having an annular recess adjacent to the reduced portion, a second bearing member in the lower portion of said bore, a clutch member within the bore and slidably in the second bearing member, means on said housing for shifting said clutch member, said clutch member having a pin therein, said drive shaft having a longitudinal slot receiving said pin, a spring in said annular recess and engaging the upper end of said clutch member, said clutch member having teeth in the lower face thereof, a post on said base member, a rotary head having an aperture fitting said post, means holding said head in place, said head having spaced apertures therein, a bearing member mounted in each head aperture, each bearing member having large upper and lower bores and an intermediate reduced bore, said reduced bore providing shoulders at each end thereof, a chuck spindle having a shank arranged in said large lower bore and having a shoulder engaging the lower of said shoulders, said spindle having an intermediate cylindrical portion in said intermediate bore and above the shoulder and having a threaded upper end in said large upper bore, a washer about said spindle intermediate portion, and a second clutch member threadedly engaging said spindle threaded portion and engaging said washer, said second clutch member having teeth in the upper face thereof, each spindle having an integral portion at the lower end thereof adapted to receive a tool.

GRAHAM C. SCATES.
